UNITED STATES PATENT OFFICE.

JOSEPH BLOCK, OF BROOKLYN, NEW YORK, ASSIGNEE TO INTERSTATE ELECTRIC NOVELTY CO., OF NEW YORK, N. Y., A CORPORATION OF NEW YORK.

PISTOL FLASH-LIGHT.

1,118,467.

Specification of Letters Patent.

Patented Nov. 24, 1914.

Application filed June 10, 1913. Serial No. 772,780.

To all whom it may concern:

Be it known that I, JOSEPH BLOCK, a citizen of the United States, and a resident of Brooklyn, in the county of Kings and State of New York, have invented certain new and useful Improvements in Pistol Flash-Lights, of which the following is a specification.

The purpose of the invention is to provide a pocket flash light in imitation of a pistol and of simplified, durable and convenient construction.

One portion of the invention pertains to the construction of the casing of the flash light, permitting the flash light to be constructed comparatively inexpensively and to be conveniently supplied with a battery and replenished with batteries as often as may be required.

Another feature of the invention pertains more particularly to the means for completing the circuit through the lamp on the pull of the trigger, it being highly desirable that this circuit shall be completed in an effective manner and without complication of moving contacts each time the trigger is pulled and held in its rearward position.

The casing portion of my new flash light comprises two shells or half casings hinged together at one edge and adapted to be latched together at the opposite edge to complete the casing, and said casing in its handle portion is adapted to detachably receive a dry or semi-dry battery, which may be replenished at any time desired. The lamp is detachably secured in the outer end of the barrel portion of the piston-casing and the trigger is provided within the casing with the conductor, one end of which is always in engagement with one of the conductors from the battery and the other end of which is adapted on the pull of the trigger to be placed in electrical engagement with the lamp, so as to complete the circuit from the battery through the casing and lamp.

The invention will be fully understood from the detailed description hereinafter presented, reference being had to the accompanying drawings, in which:

Figure 1 is a side elevation of a pistol flash light constructed in accordance with and embodying my invention; Fig. 2 is a front end view of the same; Fig. 3 is a side elevation of the same, with the two parts of the casing of the flash light opened outwardly

from each other, the lamp being carried by one-half section of the casing and the battery and trigger by the other half-section thereof; Fig. 4 is a longitudinal section, partly broken away, through a portion of the flash light, showing the relation of the conductor carried by the trigger to the lamp when the two parts of the casing are closed together and the trigger is in its normal or non-operated position; Fig. 5 is a vertical transverse section through the flash light about on the dotted line 5—5 of Fig. 3, and Fig. 6 is a vertical transverse section through a portion of the casing of the flash light on the dotted line 6—6 of Fig. 1 and is presented to illustrate more particularly the latch at the upper side of the casing for releasably locking the two sections of the casing of the flash light together.

In the drawings, 10 designates the exterior casing of the flash light as a whole, and this casing is, as shown, formed of two substantially corresponding longitudinal sections 11, 12 hinged together, as at 13, at their lower edges and provided at their upper edges with a suitable latch for locking the two sections together, said latch comprising a spring bar 14 secured to the inner upper side of the section 12 by means of a rivet 15 and having at its forward end an opening 16 adapted to, upon the closing of the two sections of the casing together, snap upon and receive the lower end of a stud 17 secured to the section 11 of the casing. The spring bar 14 has secured to it an upwardly extending finger-piece 18, which, when depressed, will carry the forward end of the spring 14 and aperture 16 therein from the lower end of the stud 17 and permit the two sections of the casing to be opened outwardly on the hinge 13, to the position shown in Fig. 3. The casing sections 11, 12 when closed together present an outline in imitation of a pistol or revolver having a handle portion and a barrel portion, the section 11 having pivotally secured to it a trigger 19 protected by a guard 20 riveted to said section. The casing sections 11, 12 are hollow sheet metal matching shells, and within these shells is formed a chamber 21, in the handle portion, to receive a suitable battery 22, while within the barrel portion of the shells is created a chamber 23 to receive the upper end of the battery 22, the conductors 24, 25 extending therefrom, the

conductor 26 carried upon but insulated from the upper end of the trigger 19, and the supports 27, 28 for the conductors 24, 25, the support 27 being of metal and in electrical engagement with the conductor 24 and section 11 of the casing, and the support 28 being of vulcanized fiber or other suitable non-conducting material and held by a sheet metal clip 29 fastened to the inner surface 10 of the section 11 by means of the pin 30 by which the trigger 19 is secured in place. The support 27 is located in the upper rear, or what may be called, hammer portion, of the casing and is a strip of metal 15 having at its lower end a laterally extended ear secured by a rivet 31 to the casing section 11. The upper end of the support 27 is recessed, at 32, to receive the terminal or conductor 24, the insertion of said conductor 20 edgewise into said recess serving to materially aid in holding the battery 22 firmly in position. The support 28 is also recessed, as at 33, to receive edgewise the battery terminal or conductor 25, and this 25 manner of holding the conductor 25 also aids in the firm positioning of the battery 22 within the handle portion of the casing. The lower portion of the casing or shell of the flash light rather snugly receives the 30 battery 22, as shown in Fig. 3, and said battery when placed within the casing with its terminals or conductors held by the supports 27, 28 is practically immovable, but may, of course, be readily detached upon the opening 35 of the casing.

The trigger 19 is formed from a piece of sheet metal and mounted on the pin 30, on which is placed a coiled spring 34 which acts to throw the lower end of the trigger forwardly and whose force must be overcome on pulling the trigger to flash the light. Upon the upper end of the trigger is formed a rearwardly extending plate 35 having lips 36 to clip upon the strip of vulcanized fiber 45 or other insulating material 37, upon which the conductor 26, hereinbefore referred to, may be secured by riveting, as at 38 (Fig. 4).

The outer end of the casing section 12 is 50 provided with a socket 39 to receive the lamp 40 in a familiar manner, and when the parts of the casing are together the terminal 41 at the inner end of the lamp stands in near relation to but free of the forward 55 end of the conductor 26, as shown in Fig. 4. When the trigger 19 is pulled rearwardly it rocks the conductor 26 and the forward end of the latter passes into electrical engagement with the terminal 41 of the lamp and 60 completes the circuit by which the lamp is lighted. The conductor 26 is an integral strip of metal having its forward end bent upwardly to assuredly engage the terminal 41 of the lamp. The rear end of the conductor 26 is also bent upwardly and remains 65

in permanent engagement with the battery terminal 25, which is a thin strip of spring metal against which the upwardly extending rear end of the conductor 26 may ride when the trigger 19 is pulled rearwardly.

The pistol as a whole has been designed with the view of attaining efficiency with simplicity and durability of construction.

What I claim as my invention and desire to secure by Letters Patent, is:

1. A flash-light comprising an exterior casing composed of two longitudinal hollow shells imitating the handle and barrel portions of a pistol, a trigger carried by one of said shells, an electric lamp in said barrel portion, a battery in said handle-portion having one terminal in engagement with said casing, and a contact-conductor on said trigger having one end to engage the other battery terminal and its other end to engage the lamp-terminal when the trigger is pulled.

2. A flash-light comprising an exterior casing composed of two substantially corresponding matching longitudinal hollow shells imitating the two vertical longitudinal halves of the handle and barrel portions of a pistol and adapted to be opened outwardly from each other, a trigger carried by one of said shells, an electric lamp in said barrel portion, a battery in said handle portion having terminals, and a contact-conductor on said trigger having one end to engage one of said terminals and the other end to engage the lamp-terminal when the trigger is pulled.

3. A flash-light comprising an exterior casing composed of two substantially corresponding matching longitudinal hollow shells imitating the two vertical longitudinal halves of the handle and barrel portions of a pistol and adapted to be opened outwardly from each other, said shells being hinged together at the lower edge of said handle-portion and provided with spring latching means at the upper edge of said barrel-portion, a trigger carried by one of said shells, an electric lamp in said barrel portion, a battery in said handle portion having terminals, and a contact-conductor on said trigger having one end to engage one of said terminals and the other end to engage the lamp-terminal when the trigger is pulled.

4. A flash-light comprising an exterior casing composed of two substantially corresponding matching longitudinal hollow shells imitating the two vertical longitudinal halves of the handle and barrel portions of a pistol and adapted to be opened outwardly from each other, a trigger carried by one of said shells, an electric lamp socket and an electric lamp therein carried in the end of the barrel-portion of one of said shells, a battery held in the handle portion of one of said shells and having terminals,

4. A conducting support in said shell connected therewith and recessed to receive one of said terminals, a non-conducting support in said shell recessed to receive the other of said terminals, and a contact-conductor on said trigger having one end to engage said other terminal and the other end to engage the lamp-terminal when the trigger is pulled.
5. A flash-light comprising an exterior casing composed of two substantially corresponding matching longitudinal hollow shells imitating the two vertical longitudinal halves of the handle and barrel portions of a pistol and adapted to be opened outwardly from each other, a trigger carried by one of said shells, an electric lamp socket and an electric lamp therein carried in the barrel portion of the other of said shells, a battery in the handle portion of the shell having the trigger and having a terminal in electrical engagement with said shell and also a second terminal, and a contact-conductor on said trigger having one end to engage said second terminal and another end to engage the lamp-terminal when the trigger is pulled.
6. A flash-light comprising an exterior casing composed of two substantially corresponding matching longitudinal hollow shells imitating the two vertical longitudinal halves of the handle and barrel portions of a pistol and adapted to be opened outwardly from each other, a trigger carried by one of said shells, an electric lamp in said barrel-portion, a battery within said casing having one terminal in electrical engagement therewith, and a contact-conductor operable on the pull of said trigger to connect the other battery-terminal with the lamp.
7. A flash-light comprising an exterior casing composed of two substantially corresponding matching longitudinal hollow shells imitating the two vertical longitudinal halves of the handle and barrel portions of a pistol and adapted to be opened outwardly from each other, said shells being hinged together at the lower edge of said handle-portion and provided with spring latching means at the upper edge of said
- barrel-portion, a trigger carried by one of said shells, an electric lamp in said barrel-portion, a battery within said casing having one terminal in electrical engagement therewith, and a contact-conductor operable on the pull of said trigger to connect the other battery-terminal with the lamp.
8. A flash-light comprising an exterior casing composed of two substantially corresponding matching longitudinal hollow shells imitating the two vertical longitudinal halves of the handle and barrel portions of a pistol and adapted to be opened outwardly from each other, said shells being hinged together at the lower edge of said handle-portion and provided with spring latching means at the upper edge of said barrel-portion, an electric lamp in said barrel portion, a battery in said handle portion having terminals, a movable contact-conductor having one end to engage one of said terminals and the other end to engage the lamp-terminal, and means for moving said contact-conductor.
9. A flash-light comprising an exterior casing composed of two substantially corresponding matching longitudinal hollow shells imitating the two vertical longitudinal halves of the handle and barrel portions of a pistol and adapted to be opened outwardly from each other, an electric lamp socket and an electric lamp therein carried in the end of the barrel-portion of one of said shells, a battery held in the handle portion of one of said shells and having terminals, a conducting support in said shell connected therewith and recessed to receive one of said terminals, a non-conducting support in said shell recessed to receive the other of said terminals, a movable contact-conductor having one end to engage said other terminal and the other end to engage the lamp-terminal, and means for moving said contact-terminal.

Signed at New York city, in the county of New York and State of New York, this 9th day of June A. D. 1913.
